AU 292 EX
OR D 18,182

Design No. 18,182, dated March 13, 1888.

UNITED STATES PATENT OFFICE.

WOLDEMAR SCHREYER, OF BROOKLYN, ASSIGNOR TO McLAUGHLIN
BROTHERS, OF NEW YORK, N. Y.

DESIGN FOR A BOX.

SPECIFICATION forming part of Design No. 18,182, dated March 13, 1888.

Application filed December 27, 1887. Serial No. 259,136. Term of patent 7 years.

To all whom it may concern:

Be it known that I, WOLDEMAR SCHREYER, a citizen of the United States, and a resident of Brooklyn, Kings county, New York, have 5 invented and produced a new and original Design for a Box, of which the following is a specification, reference being had to the accompanying photograph, forming a part thereof.

The figure is a perspective view of the newly-10 designed box, showing the front, the top, and one end. This view is sufficient to illustrate my design, as the back of the box presents substantially the same appearance as the front, and the designs on the ends of the box are 15 alike.

A is the body of the box, and B the cover thereof. The designs on the body and cover are of the same general character, and harmonize both in style and arrangement, the stripes 20 and other elements of the design on both parts of the box being made to register in such a manner as to present the appearance of being continuous, in the manner and to the extent that will be hereinafter set forth and as will be seen in the accompanying photograph.

The box is rectangular in its configuration, and at its angles are dark stripes a a, which extend up the front, back, and ends of the box and across the top and ends of the cover. On 30 these stripes are parallel rows of light-colored dots extending lengthwise of the stripes, as shown. About half-way between the middle of the box and its ends are two broad dark stripes, b b, which extend up the front and back of the box and across the cover. On each 35 of these stripes are two parallel rows of light-colored dots, and also, at intervals, numerals of a light color, each surrounded by a circle. At the lower edge of the cover, and extending 40 around the same, is a dark stripe, c, on which is a row of light-colored dots extending lengthwise of the stripe. This stripe c intersects the stripes a and b at right angles. At the lower edge of the box, and extending all around the

same, is a stripe, d, made up of parallel lines, 45 and about half-way up the side of the body of the box is a similar stripe, e, parallel with stripe d. On the top of the cover of the box are five parallel stripes, f f, each made up of lines and extending lengthwise of the box. The several 50 stripes d, e, and f intersect the stripes a and b at right angles. At the middle of the upper edge of the front of the box, and extending down from stripe c to stripe e, is a design, g, representing a lock and hasp. On the various panels or rectangular spaces formed by the crossing stripes are designs h h, representing conventionalized flowers. On the top of the cover of the box is the representation of a scroll, i, arranged obliquely with respect to 60 the stripes b b and partly overlapping said stripes at its respective ends.

I claim—

The design for a box herein shown and described, the same consisting of the dark stripes 65 a a at the angles of the box, the broad dark stripes b b, parallel with the stripes a a, said stripes a and b extending around the box and having each two rows of dots, the dark stripe c, extending around the box and intersecting 70 the stripes a and b at right angles, the stripes d and e, made up of lines extending around the box parallel with stripe c, the stripes f, made up of lines on the top of the box and extending lengthwise of the same, the representation, 75 g, of a lock on the front of the box, the conventionalized representations of flowers h h in the panels formed by the stripes, and the representation, i, of a scroll on the top of the box, substantially as set forth.

In witness whereof I have hereunto signed my name in the presence of two subscribing witnesses.

WOLDEMAR SCHREYER.

Witnesses:

HENRY CONNETT,
J. D. CAPLINGER.
